UNITED STATES PATENT OFFICE.

GEORGE M. BATES, OF LEBANON, MISSOURI.

FARM-GATE.

1,155,463.

Specification of Letters Patent.

Patented Oct. 5, 1915.

Application filed February 20, 1915. Serial No. 9,617.

To all whom it may concern:

Be it known that I, GEORGE M. BATES, a citizen of the United States, residing at Lebanon, in the county of Laclede and State of Missouri, have invented certain new and useful Improvements in Farm-Gates, of which the following is a specification.

This invention relates to improvements in gates, more particularly to the class of gates adapted to be operated from a distance by a person in a vehicle or on horseback without alighting, and has for one of its objects to improve and strengthen the construction of the gate and its supports.

With this and other objects in view, the invention consists in certain novel features of construction as hereinafter shown and described and then specifically pointed out in the claims; and in the drawings illustrative of the preferred embodiment of the invention Figure 1 is a perspective view of the improved gate; Fig. 2 is a section on the line 2—2 of Fig. 1; Fig. 3 is a section on the line 3—3 of Fig. 1; Fig. 4 is a detached perspective view of the hinge support of the gate.

Corresponding and like parts are referred to in the following description and indicated in all the views of the drawings by the same reference characters.

The improved gate is constructed of end members 10—11, each formed of two portions spaced apart, horizontal rails 12 connected at their ends between the spaced end members, and diagonal braces 13. One of the rails 12 is replaced by a sliding member 14 extending at its ends between the spaced end members 10—11. At one end, the member 14 forms a latch or lock, as represented at 15 to engage in a slot or socket, indicated at 16 in the latch post 17, while a leaf spring 18 is connected to the end members 10 and bears against the opposite end of the member 14 and maintains the latter yieldably with its terminal 15 in the socket 16, and holds the gate in locked or closed position.

Blocks 19 are connected to the opposite sides of the rail 12 next below the member 14, while similar blocks 20 are connected to the opposite sides of the member 14. Pins 21 project laterally from the blocks 20, as shown. Pivoted at 22 to the blocks 19 are straps or plates 22' which engage normally against the pins 21 to move the member 14 endwise and withdraw the terminal 15 from engagement with the socket 16 and thus re-

lease the gate when the operating mechanism is applied, as hereafter explained.

Attached to the end members 10 of the gate, at opposite sides, are relatively large blocks 23. A supporting rod, bent into U-shape to form spaced sides 24—25, is connected at its ends in the blocks 23 and passed at its bend through the lowermost rail member 12 near the end members 11 of the gate. The terminals of the bent rod are located in the blocks 23 near their outer edges, so that the sides 24—25, where they pass through the blocks 23, are located at a considerable distance apart, and thus apply a bracing force to the gate when open. An intermediate supporting member 26 is located upon the lowermost member 12 and engages the side portions 24—25 of the rod and thus prevents sagging of the latter at the center.

The end members 10 of the gate extend for a considerable distance above the upper rail 12, while the end members 11 likewise extend above the uppermost rail 12. The end members 10 are connected by a transverse bolt 27 which passes through the upwardly extending portions of the same, while a similar tie bolt 28 passes through the upwardly extending portions of the end members 11. A tie rod 29 connects the bolts 27—28, and materially strengthens and supports the upper portion of the gate. The uppermost rail member 12 extends beyond the outer edges of the end members 11 and is adapted to engage in a notch 30 in the upper end of the post 17. At its lower end, the inner face of the post 17 is provided with guide chocks 31—32 to receive the lower ends of the end members 11 when the gate is disposed in closed position.

A pivot member 33 extends through the blocks 23, and the gate is opened by swinging bodily upon this pivot. At its terminals, the pivot 33 passes through vertical posts 34—35, the latter being substantially equal in height to the end members 10 of the gate to carry the terminals of the strand wires of the fence, indicated at 38, at one side of the gateway opening, while the post 34 may be shorter than the post 35, as shown. The pivot rod 33 is stationary and serves as a tie rod to the posts 34 and 35. The posts 34—35 are spaced apart a distance equal to the combined width of the end members 10 and the blocks 23 so that the gate swings upwardly between the posts. The posts 34—35 are connected at their

lower ends by a transverse member 36, and likewise connected intermediate their ends by a transverse member 37. The posts will be embedded in the ground to a sufficient depth to entirely cover the members 36-37, which then act as stays to support and hold the posts in spaced relation, and effectually preventing any lateral or other movement of the posts, and thus maintaining the gate constantly in operative position and effectually preventing all displacement of the posts by the action of the frost or other means, the posts 34-35 being of sufficient length so that the transverse member 36 is constantly located below the frost line.

Any suitable means may be employed for actuating the arms 22', but for the purpose of illustration, pull rods or cables 39 are shown and connected, respectively, to the arms 22' and lead to suitable devices located at opposite sides of the gate, but not illustrated, as it forms no part of the present invention. The pull devices are so located that a person approaching the gate may actuate the same without alighting from a vehicle or from horseback, and thus pull the gate into vertical and open position by causing it to swing upon its pivot 33, as will be obvious. At the first operation of either one of the pull members 39, the member 22', which is, for the time being, connected thereto, is actuated, and exerting a pulling force upon the adjacent pin 21 and moves the member 14 longitudinally against the resistance of the spring 18 and withdraws the terminal 15 from the socket 16 to release the gate which is then drawn into vertical position by a continued pull upon the member 39.

By this arrangement a very strong and durable gate support is produced, and the

gate materially strengthened and supported against displacement while in use.

Having thus described the invention, what is claimed as new is:

1. In a device of the class described, a gate including end members and connecting rails, laterally directed bearing members carried by said gate at one end and at opposite sides thereof, vertical posts spaced apart, a tie rod extending through said vertical posts and through said bearing members, and a rod bent intermediate its ends to form side portions and extended at its bend through one of the rails near its free end and the sides of the rod diverged and connected to the bearing members, and a clip device engaging the sides of the rod and holding the outer portions thereof in close engagement with the adjacent rail.

2. In a device of the class described, a gate including end members and connecting rails, laterally directed bearing members carried by said gate at one end and at opposite sides thereof, vertical posts spaced apart, a tie rod extending through said vertical posts and through said bearing members, a rod bent intermediate its ends to form side portions and extended at its bend through one of the rails near its free end and the sides of the rod diverged and connected to the bearing members, and a clip device having eyes engaging the rod and bearing over the adjacent rail and holding the outer portions of the rod in close engagement with the adjacent rail.

In testimony whereof I affix my signature in presence of two witnesses.

GEORGE M. BATES. [L.S.]
